UNITED STATES PATENT OFFICE.

JOHN DAY, OF NEW YORK, N. Y.

DESIGN FOR A STAIR-CARPET FASTENER.

SPECIFICATION forming part of Design No. 23,158, dated March 27, 1894.

Application filed February 28, 1894. Serial No. 501,877. Term of patent 7 years.

To all whom it may concern:

Be it known that I, JOHN DAY, a citizen of the United States, residing in the city, county, and State of New York, have invented and produced a new and original Design for a Stair-Carpet Fastener, of which the following is a specification, reference being had to the accompanying drawings, forming part hereof, wherein—

10 Figure 1 is an orthographic front elevation of a stair carpet fastener embodying my design. Fig. 2 is a transverse central vertical section through the same.

15 This invention relates to a new design for stair carpet fasteners, the same consisting in

a stair carpet fastener in the shape of a quadrant of an ovoid on the axis of revolution thereof, as shown in the drawings, in which—

20 A represents the stair carpet fastener, and a b the line of the axis of revolution.

c indicates a perforation in the stair carpet fastener designed to allow the passage of a nail or other securing means.

What I claim is—

25 The design for a stair carpet fastener, substantially as herein shown and described.

JOHN DAY.
